Primary Examiner — Michael C Stout*Assistant Examiner* — Laura H Yu(74) *Attorney, Agent, or Firm* — Banner & Witcoff, Ltd.(57) **CLAIM**

The ornamental design for a shoe, as shown and described.

DESCRIPTION

FIG. 1 is a photographic bottom view of a shoe showing my new design;

FIG. 2 is a side view thereof; and,

FIG. 3 is an opposite side view thereof.

The broken lines immediately adjacent to the darker grey photographic portions represent the bounds of the claimed design and form no part thereof. The lighter grey photographic portions on the midsole periphery and the entire shoe upper are for the purpose of illustrating environment and form no part of the claimed design.
